[57] CLAIM

The ornamental design for a window latch, as shown and described.

DESCRIPTION

FIG. 1 is a side view of a window latch according to one preferred embodiment of this invention;

FIG. 2 is a side view opposite the side view of the window latch as shown in FIG. 1;

FIG. 3 is a top view of the window latch as shown in FIG. 1;

FIG. 4 is a bottom view of the window latch as shown in FIG. 1;

FIG. 5 is a front view of the window latch as shown in FIG. 1; and,

FIG. 6 is a rear view of the window latch as shown in FIG. 1.

The broken lines are shown for illustrative purposes only and form no part of the claimed design.
